UNITED STATES PATENT OFFICE.

GEORGE H. BALCH, OF NEWBURYPORT, MASSACHUSETTS, ASSIGNOR TO THE
TOWLE MANUFACTURING COMPANY, OF SAME PLACE.

DESIGN FOR A SPOON, &c.

SPECIFICATION forming part of Design No. 20,743, dated May 19, 1891.

Application filed April 18, 1891. Serial No. 389,605. Term of patent 7 years.

To all whom it may concern:

Be it known that I, GEORGE H. BALCH, of Newburyport, Massachusetts, have invented a Design for the Handles of Spoons and other Flat Ware, of which the following is a full, 5 clear and exact description.

Reference is to be had to the accompanying drawing, forming a part of this specification, in which the figure represents a face view of a 10 spoon having my new design produced in the handle thereof.

The design consists in the ornamentation arranged relatively to and in connection with a plain or unornamented surface, the opposed 15 edges of the ornamented and unornamented surfaces being disposed approximately in a diagonal line.

The letter *a* indicates the plain surface, and *b* the ornamented surface, the latter comprising a fanciful scroll *b'* and trefoils *b²* *b³*, the starting-point of the scroll being between the trefoil figures and its end terminating in oppositely-curving branches *b⁴* *b⁵*. The meeting edges or opposed edges of the ornamented and unornamented surfaces are disposed in a general diagonal direction. 20 25

I claim—

The design for the handles of spoons and other flat ware herein shown and described.

GEORGE H. BALCH.
